SAFETY LOCK FOR SEMITRAILERS

Donald Earl Bramble, Chicago, Ill.

Application April 2, 1943, Serial No. 481,619

3 Claims. (Cl. 280—33.1)

The present invention relates to new and useful improvements in semi-trailers, and has for its primary object to provide, in a manner as hereinafter set forth, novel means for automatically locking the trailer to the tractor when the usual landing gear of the former is raised to inoperative position, thereby positively preventing separation of the two until said landing gear is again lowered.

Other objects of the invention are to provide an automatic safety lock of the aforementioned character for semi-trailers which will be comparatively simple in construction, strong, durable, highly efficient and reliable in use, compact, light in weight, and which may be manufactured and installed at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a perspective view, showing an embodiment of the invention installed for operation on a semi-trailer equipped with a landing gear of the swinging type.

Figure 2 is a view in vertical longitudinal section through the front portion or nose of the semi-trailer.

Figure 3 is a cross-sectional view, taken substantially on the line 3—3 of Figure 2.

Figure 4 is a view in side elevation of an embodiment of the invention which is for installation on semi-trailers which are equipped with landing gears of the vertically movable type, the shaft of the safety lock being shown in cross-section.

Figure 5 is a cross-sectional view, taken substantially on the line 5—5 of Figure 4.

Figure 6 is a perspective view of the pivoted lever-supporting frame.

Figure 7 is a detail view in perspective of the lever.

Referring now to the drawings in detail, and to Figures 1, 2 and 3 thereof in particular, it will be seen that reference numeral 1 designates a metallic arm which is welded longitudinally on the pivoted end portion of the usual leg 2 of a conventional semi-trailer landing gear 3 of the swinging type. A forwardly extending metallic rod 4 is pivotally and adjustably secured at its rear end, as at 5, to the free end portion of the arm 1. A depending guide 6 is provided for the

rod 4 on one of the frame members 7 of the semi-trailer 8.

- 5 A transverse shaft 9 is journaled in openings which are provided therefor in the longitudinal frame members 10 of the semi-trailer 8 above the fifth wheel plate 11 of said semi-trailer and forwardly of the king pin 12. An arm 13 is fixed on one end portion of the shaft 9, to which arm the forward end of the rod 4 is pivotally connected. 10 A dog 14 is fixed on the shaft 9 at an intermediate point. The dog 14 is operable in a longitudinal slot 15 which is provided therefor in the fifth wheel plate 11 forwardly of the king pin 12. 15 The dog 14 is also operable between a pair of angular brackets 16 (see Fig. 3) which are welded on the fifth wheel plate 11 on opposite sides of the slot 15. The shaft 9 is journaled in openings which are provided therefor in the brackets 16. 20 A bar 17 of angle iron is welded transversely on the fifth wheel plate 11 at the forward end of the slot 15 for supporting the dog 14 when it is in operative position.

It is thought that the operation of the device 25 will be readily apparent from a consideration of the foregoing. Briefly, when the landing gear 3 is in lowered position, the dog 14 is in raised or inoperative position, as illustrated in dotted lines in Figures 1 and 2 of the drawings. Thus, the 30 tractor may be connected to or disconnected from the semi-trailer in the usual manner. When the tractor has been connected to the semi-trailer and the landing gear 3 is swung upwardly, the members 1, 4 and 13 rock the shaft in a direction to swing the dog 14 downwardly to a substantially vertical position through the slot 15 into abutting engagement with the bar 17, thereby positioning the lower end portion of said dog in the forward path of the fifth wheel 18 of the 35 tractor. It will thus be seen that the tractor 40 cannot pull away from the semi-trailer so long as the landing gear 3 is in raised or inoperative position. The device also functions as a safety lock in the event of failure of the usual fifth 45 wheel lock of the tractor.

In the embodiment illustrated in Figures 4 to 6, inclusive, of the drawings, a depending plate 19 is fixed beneath the frame structure of the semi-trailer adjacent the vertically movable landing gear 20 of said semi-trailer. Mounted on the plate 19 is a pair of brackets 21. The brackets 21 support a frame 22.

A lever 23 is pivotally mounted, at an intermediate point, in the upper front portion of the frame 22 for swinging movement in a vertical

plane. The lever 23 includes a substantially rounded end portion to which one end of the dog-operating rod 4 is pivotally connected, as at 24. A return spring 25 is connected to the other end portion of the lever 23. A vertical bar 26 is mounted on the axle 27 of the landing gear 20. The upper end portion of the bar 26 is slideable in the frame 22 for engagement with the lever 23 for actuating said lever against the tension of the spring 25. In other respects the construction of this form of the invention is substantially similar to the embodiment illustrated in Figures 1, 2 and 3 of the drawings.

In operation, when the landing gear 20 is raised, the upper portion of the vertical bar 26, traveling in the frame 22, engages and rides on the rounded end portion 28 of the lever 23, thereby swinging said lever in a direction, against the tension of the spring 25, to move the rod 4 forwardly, thus swinging the dog 14 downwardly to operative position, as seen in dotted lines in Figure 4 of the drawings. When the landing gear 20 is lowered, the bar 26 drops therewith and the spring 25 actuates the lever 23 for returning the dog 14 to raised or inoperative position. In addition to supporting the lever 23, the frame 22 functions as a guide for the bar 26.

It is believed that the many advantages of an automatic safety lock for semi-trailers constructed in accordance with the present invention will be readily understood, and although preferred embodiments of the device are as illustrated and described, it is to be understood that further modifications and changes in the details of construction may be resorted to which will fall within the scope of the invention as claimed.

What is claimed is:

1. An automatic safety lock for semi-trailers of the type having a retractible landing gear, a fifth wheel plate and a depending king pin engageable with the fifth wheel of a tractor, comprising a pair of brackets mounted on the fifth wheel plate, said fifth wheel plate having a longitudinal slot therein between the brackets and forwardly of the king pin, a transverse shaft journaled in the brackets and in the frame structure of the semi-trailer, a transverse bar fixed on the fifth wheel plate at the forward end of the slot, a dog fixed on the shaft between the brackets and operable for forward movement in the slot for positioning in front of the fifth wheel of the tractor for engagement therewith for preventing separation of said tractor from the semi-trailer, said dog, when in operative position, being engageable with the bar to provide a reinforcing stop for the dog, and means operatively connecting the shaft to the landing gear for forwardly swinging the dog to operative position when said landing gear is moved to inoperative position.

2. A safety lock for semi-trailers having a swinging landing gear, a fifth wheel plate and a king pin depending therefrom for connection with the fifth wheel of a tractor, said fifth wheel plate having a longitudinal slot therein forwardly of the king pin, said safety lock comprising an upstanding arm fixed on the pivoted end portion of the landing gear, a transverse shaft journaled on the trailer above the fifth wheel plate and forwardly of the king pin, a dog fixed on the shaft and operable in the slot for forward movement and engagement with the tractor fifth wheel, a stop at the front end of the slot and engageable by the dog to limit forward movement of the dog, an arm fixed on the shaft, and a rod connecting the second-named arm to the first-named arm for rocking the shaft for swinging the dog to operative position when the landing gear is retracted.

3. A safety lock for trailers having a vertically movable landing gear, a fifth wheel plate having a longitudinal slot therein and a king pin depending from said plate rearwardly of the slot, said safety lock comprising a frame mounted on the semi-trailer adjacent the landing gear, a lever pivotally mounted on said frame, a transverse shaft journaled on the semi-trailer above the fifth wheel plate and forwardly of the king pin, a dog fixed on said shaft and operable in the slot for engagement with a fifth wheel of a tractor and arranged for forward and backward movement, a rod operatively connecting the lever to the shaft for swinging the dog to operative position, and a bar on the landing gear for movement therewith, said lever being in the path of retraction movement of the landing gear to actuate the dog into its locking position.

DONALD EARL BRAMBLE.
